FILAMENT SUPPORT STRUCTURE

Frank Douglas Goodchild, London, England, assignor to International Standard Electric Corporation, New York, N. Y., a corporation of Delaware

Application November 29, 1947, Serial No. 788,785
In Great Britain October 16, 1946

Section 1, Public Law 690, August 8, 1946
Patent expires October 16, 1966

8 Claims. (Cl. 250—27.5)

1

The present invention relates to supporting means for filaments which are adapted to be heated by means of electric current passed therethrough and is directed towards means for preventing distortion of the filament or filaments carried by the said supporting means due to unequal thermal expansion of parts thereof. In particular the invention is concerned with supporting means which comprise rods which support the filament wire or wires and which are of unequal length.

Heating filaments and the supporting means therefor are used to a large extent in electric lamps and in electron discharge devices. In many of these, the filaments are carried by means of rods which also supply the heating current. According to the general constructional form of the device of which the filament and its supports form a part, these rods may not all be of the same length with the consequence that there is a tendency for them to be subject to different thermal elongations with consequent distortion of the filament wires. It is usually easier to compensate for equal thermal distortions than for unequal expansions or contractions at the filament ends of the rods. Although here and throughout the description which follows attention will be directed towards the case of a filament structure for an electron discharge device, the present invention is not limited in its application to such devices.

The present invention consists in a supporting means for filament or filaments adapted to be heated by means of electric current passed therethrough and comprising filament supporting rods of unequal length in which said rods are secured to rigid transverse members at substantially equidistant distances from their filament ends and are supported at the ends remote from the filament by means flexibly positioning said rods of unequal length in relation to each other, said rigid transverse members being locked together to prevent differential thermal extension of said rods with respect to one another at their filament ends.

As applied to a particular embodiment to be described the invention provides a filament supporting means for a high power electron discharge device comprising a pair of tubes of conducting material, one concentrically within the other, for supplying current to said filament, said tubes being hermetically sealed to either end of a barrel shaped member of vitreous material which surrounds said inner tube and forms a continuation of said outer tube, a first platform of conducting material mounted upon said inner tube at right angles thereto and at the end thereof which is sealed to said vitreous member, said platform

2

carrying supporting rods for one set of filament wires, a thin metallic disc attached to said outer tube near its junction with said vitreous member and carrying supporting rods for another set of filament wires, each set of said rods passing through and being rigidly attached to a second and a third platform, respectively, said filament supporting means being characterised in this that the said second and third platforms are substantially equidistant from the filament ends of the respective sets of rods to which they are attached and are rigidly secured together so that differential thermal expansion of said rods is prohibited on the filament side of said platforms and may be taken up at the other ends of the sets of rods by virtue of the flexibility of said thin metallic disc.

The invention will now be described by way of example in a particular embodiment for a high power electron discharge device as illustrated in the accompanying drawing in which Fig. 1 is a sketch of the filament support and Fig. 2 a sketch of a detail thereof.

Fig. 1 of the drawing illustrates a filament supporting structure which is carried in an electron discharge device by means securing the outer tube 1 of a pair of concentric tubular current conductors to the envelope of the device. The tube 1 is provided at its lower end with a flared cone 2 to which is sealed a barrel shaped member 3 of glass or similar vitreous material. The inner tubular conductor 4 is similarly sealed to the other end of member 3 at 5 and carries a platform 6 upon a member closing the end of the tube 4. This general form of construction is described more fully and is claimed in U. S. Patent No. 2,465,369, issued March 29, 1949, to W. T. Gibson entitled "Current lead-in seal for electric vacuum tubes and the like." The platform 6, which is of copper, has brazed to its corners copper support rods 7. At the upper end of member 3 a thin circular disc 8 of copper is brazed to the outer tube 1 and carries three copper rods 9 secured thereto by adjusting collars 10 and nuts 11 on the underside of disc 8. The rods 7 and 9 lie at the corners of a regular hexagon centered on and at right angles to the axis of the structure. The rods have extensions 7' and 9' respectively. These extension pieces are of molybdenum and fit into recesses in the ends of the copper rods where they are held by means of grub screws 11. The rods 7 and 9' pass through holes in the corners of the respective platforms 12 and 13, which are of nickel, and to which the rods are brazed. The rods 7' and 9' continue up into the tubular anode (not shown) of the discharge device and terminate on further platforms 14 and 15 respectively. A number of filament anchors

16 and 17 fit onto the respective platforms 14 and 15. In the embodiment illustrated there are nine such anchors attached to each platform. Anchors 16 are longer than anchors 17 so that the tops of both sets are at the same height along the axis of the assembly. Filament wires 18 are welded to the anchors 16, 17 at their upper ends and to molybdenum angle shaped members 19 at their lower ends. Members 19 are secured together to form a spectron held by center piece 20 which has a sliding fit into a collar which may be fixed to another part of the discharge device, such as by insulating means to grid support rods which are not shown. In operation the discharge device is mounted vertically so that the filament wires are held in tension under gravity, equal changes in length being permitted by center piece 20 sliding axially within its supporting collar. Provided the expansion for each of the sets of rods and wires are the same, thermal movement is thus taken up. The rods 1 and 9, however, are not of the same length and a difficulty is presented, particularly if say, some eighteen kilowatts of power are to be dissipated by the filament and hence the supporting rods are also correspondingly heated. In order to overcome this difficulty we lock together the two platforms 12 and 13 by means of an insulating spacer 21 and bolt 22. Furthermore the platforms 12 and 13 are equidistant from the lower ends of their respective molybdenum rods. Hence all the parts below platforms 12 and 13 are constrained to move together, while the resilience of the thin copper disc 8 takes up the differential extension of the rods 9 with respect to rods 1. In order to provide greater flexibility the disc 8 may be slotted as shown. The method of locking the platforms 12 and 13 together is shown more clearly in Fig. 2. The platforms 12 and 13 fit into shaped portions of insulating collar 21 and are held by means of a further insulator 23, collars 24 and 25 and nuts 26, 27 to the central bolt 22. After assembly the nuts 26 and 27 are welded to bolt 22 as shown at 28 and 29.

It will be appreciated that in this embodiment the platforms 12 and 13 are provided and locked together rather than locking together platforms 14 and 15 as the latter are in a region of excessively high temperature during operation of the device. At the temperatures likely to obtain in this region ceramic insulating material for the locking means could be used.

Although the above description has been related to a particular embodiment of the invention in an electron discharge device, it will be apparent that, as stated previously, the invention may be applied with advantage to any filament supporting structure wherever filament wires adapted to be heated by electric current, are supported by rods of unequal length.

What is claimed is:

1. Filament support structure comprising a first rigid transverse member, a first set of filament supporting rods of a given length each secured at a given distance from its filament end to said first rigid transverse member, a second rigid transverse member locked to said first rigid transverse member and insulated therefrom, a second set of filament supporting rods of greater length than said given length and each secured at substantially said given distance from its filament end to said second rigid transverse member, and means adjunct said first and second sets of rods adjacent the ends remote from the filament ends flexibly posi-

tioning said sets of rods with respect to each other.

2. Filament supporting means according to claim 1 in which said rods of unequal length are each in two parts secured together, the one part being of copper and the other of molybdenum, the molybdenum part being attached to said filament.

3. Filament supporting means according to claim 2 in which said molybdenum parts of said rods are of substantially equal length.

4. Filament supporting means for a high power electron discharge device comprising a pair of concentric tubes of conducting material for supplying current to a filament, a member of vitreous material hermetically sealed between said concentric tubes, a first platform of conducting material mounted upon said inner tube at right angles thereto and adjacent the portion of said inner tube sealed to said vitreous member, a first set of filament supporting rods mounted on said first platform, a thin metallic disc attached to said outer tube near its junction with said vitreous member, a second set of relatively longer filament supporting rods mounted on said disc to compensate for relative expansion of said set of longer rods, a second platform secured to said first set of rods at a given distance from the filament ends of said first set of rods, and a third platform secured to said second set of rods at said given distance from the filament ends of said second set of rods, said second and third platforms being rigidly secured together to prevent differential thermal expansion between the filament ends of said first and second sets of rods.

5. Filament supporting means according to claim 4, in which said supporting rods of unequal length are each in two parts secured together, the one part being of copper and the other of molybdenum, each of said molybdenum parts being of substantially equal length, one end of the molybdenum part attached to said filament, said first and second platforms secured to the molybdenum parts of the respective of said rods at a point intermediate the ends thereof.

6. Filament supporting means according to claim 4 in which said first and second platforms are secured together by means of insulating collars bolted together.

7. Filament supporting means according to claim 4 in which there are six rods, three to each set, arranged hexagonally.

8. Filament supporting means according to claim 4 in which there are provided two further platforms, one to each set of rods, secured thereto adjacent the filament ends thereof.
